[57] CLAIM

The ornamental design for a handle post for luggage or the like, substantially as shown and described.

DESCRIPTION

FIG. 1 is a perspective view of a handle post for luggage or the like showing my new design;

FIG. 2 is a front elevational view thereof, with the elongated pin omitted for ease of illustration, the rear view being a mirror image thereof;

FIG. 3 is a side elevational view thereof, the opposite side being a mirror image thereof;

FIG. 4 is a top plan view thereof; and

FIG. 5 is a bottom plan view thereof.

FIG. 1

FIG. 2

FIG. 5
